STORM SHUTTER

Herbert S. Jones, Miami, Fla., assignor to
John B. Fried, Elmhurst, N. Y.

Application October 8, 1947, Serial No. 778,609

2 Claims. (Cl. 20—58)

1

This invention has to do with shutters. It is designed particularly for use as a storm shutter for protecting windows or other glazed openings. It is necessary, in shutters of this type, that they be adapted for prompt installation in event of sudden storms. Further, the construction must be such that, when erected, the shutter be so mounted and coupled as to prevent displacement under wind pressure. It is desirable also that, when not in use, removable shutter parts may be stored in a relatively small space.

These results are secured by the invention disclosed herein in which there are provided a fixed foot and header, attached to the building, designed to receive, in sliding engagement, either in horizontal or vertical assembly, a plurality of independent, separable shutter members which are brought together in overlapped, easily separable relation to form a stable awning which can be quickly installed in and removed from the front and header members, and which, when removed, can be stacked and stored in a convenient manner.

In the drawings herewith is shown one physical embodiment of the invention, and in said drawings:

Figure 1 is a perspective view of a building, one story only being shown, with the shutters in place.

Figure 2 is an enlarged detail view in elevation of a shutter holding foot and header with the shutters installed.

Figure 3 is a view in vertical section substantially on the line 3—3 in Figure 2.

Figure 4 is a view in vertical section showing a different form of foot and header construction.

Figure 5 is a detail view to show the overlapped relation of the shutters.

Figure 6 is a view in vertical section of a slightly different form of foot and header.

Figure 7 is a view in elevation of a form of the invention designed for deep windows.

Figure 8 is a view in vertical section substantially on the line 8—8 of Figure 7.

Figure 9 is an end view of a shutter.

Figure 10 is a view in perspective of the shutters stacked for storage.

Figure 11 is an enlarged view of a means for attaching a foot to the building.

Figure 12 is a view in vertical section of a door closure, and

Figure 13 is a view in horizontal section of the door closure of Figure 12.

In the drawing reference numerals are applied to designate the different parts, the same numer-

als being used for the same parts in the several views.

In Figure 1 a conventional, one-story building 10 is shown, having windows 11 and doorways 12 of usual construction insofar as frames and glazed closures are concerned. Secured to the wall of the building, as shown in Figures 2 and 3, adjacent the window opening, is a shutter holding foot made up of the L-shaped members 13 and 14 which are secured to the window ledge in any suitable manner. One satisfactory form of securing means is shown in Figure 11, in which a socket 16 embedded in the window ledge 15 is shown, which socket 16 receives the fastening screw 17 passing through the limbs of the L-shaped members 13 and 14 so as to hold them firmly in place and provide between them a channeled shutter-receiving foot for the lower ends of the shutters. At the top of the window opening is provided a header 18 of substantially inverted U-shape in cross-section to receive the upper ends of the shutters. Header 18 may be suitably secured to the wall of the building, as, for example, by means of the socket and screw construction shown in Figure 11. Preferably the header 18 will be so formed as to bind the shutters sufficiently to maintain them in close relation to one another and to the window opening. As shown in Figure 3 this result is obtained by means of an inturned lip 19 on the outer limb of header 18, which lip 19 holds the shutters closely in line.

The shutters 20, as shown in Figures 5, 9 and 10 are rectangular in form, substantially flat, and of appropriate dimensions as to length and width to permit them to be readily handled for installation and removal. In order that they may be properly overlapped to form a continuous, protective, and stable shutter when installed, the flat shutters are provided with shallow edge engaging overlapping means. As here shown, one edge of the shutter 20 is provided with slightly turned straight lip 21, while the other edge of shutter 20 is provided with an inter-engaging shallow open groove or channel 22 of substantially V-shape, in which the lip 21 is received, so as to form, as shown in Figure 1, a continuous but readily separable shutter structure. The projections formed by the lips and grooves of the shutters when assembled, fit closely the foot and header members and hold the shutters snugly in place, there being sufficient resiliency in the header lip 19 to yieldingly hold the shutters in position.

With this construction it will be seen that the

shutters may be quickly installed and removed, and, when in position, form a stable shutter. The form of the shutters and their overlapped edges are such that when not in use they can be conveniently and closely stacked in nested condition in small compass, as shown in Figure 10, for storage.

The invention may obviously be adapted to different types of windows. In Figure 4 it is shown applied to a window having an upstanding sill 23. In this form the shutter-receiving foot channel will be formed between sill 23 and an L-shaped foot member 24 secured to the ledge 25 in the manner hereinbefore described. The shutter-receiving header 26 may be the same as that shown in Figure 3.

In the form shown in Figure 6 the invention is adapted to a ledgeless window. As here shown the foot is made up of the member 27 secured to the vertical wall of the building, to which member 27 a second member 28 is secured, so as to form a shutter-receiving channel between the wall and the member 28. The header, in this form may be similar to that shown in Figures 3 and 4 and hereinbefore described.

As developed in Figures 7 and 8, the invention is designed for deep or inset and ledgeless windows. In this form the shutter-receiving channel is formed between the window frame 29 and a member of substantially inverted L-shape, the lower limb 30 of which is secured directly to the wall of the building and the upper limb 31 of which is inclined inwardly and forms, with the window frame 29 a channel for the shutters 20. In this form the header is mounted on the under-side of the opening so as to meet the requirements of the deep window opening. Preferably, this form of header will have downwardly projecting member 32 of some length to bear against the shutters 20 with yielding pressure and hold them in place, the inner member of the header lying in close relation to the window frame.

The closures for doorways 12 are shown in Figures 12 and 13. Frames 33 are provided about the door opening and transom secured to the building wall. The door and transom will be hung in the usual or any suitable fashion from frames 33. Above the transom a header 34 of the type hereinbefore described will be secured to the building wall to receive the upper end of a plate 35 which will be secured by bolts or equivalent fastening means to the frame 33 to cover the transom. At the lintel 36 of the door will be provided a foot 37 having a horizontal member to support the plate 35. With this construction plate 35 can be readily engaged with the header 34 and slipped into position on the foot 37. The door fits below the foot 37 and above

a threshold 39 and is covered by a plate 40, which plate is held in place by bars 41 bolted or otherwise secured at their ends by fastening means 42 to the frame 33 and also bolted at 43 to the cover plate 40. This construction provides a readily installed closure for the doorway.

The invention as herein disclosed provides a secure, continuous shutter for windows and doors, which can be quickly installed and removed without the need of skilled labor, and which, when not in use, can be conveniently stored in a small storage space.

Such changes from the particular construction here shown as involve only the exercise of mechanical skill and are comprehended by the appended claims may be made without departing from the spirit of the invention.

I claim:

1. A demountable shutter structure of the class described including a fixed channeled foot, a spaced channeled header in alignment with said foot, a plurality of independently insertable and separately removable shutter members slidably mounted in said foot and header, each of said shutter members having a substantially V-shaped groove at one end and an angularly disposed flat inclined lip at its opposite end, each inclined lip arranged to overlap and removably to engage the adjacent side of a V-shaped groove in an adjacent shutter member when the parts are assembled so as to provide a continuous shutter structure, and each channeled header having resilient means for yieldably maintaining the shutter members therein.

2. A demountable shutter structure as called for in claim 1 in which the channeled foot includes a separate substantially L-shaped arm arranged to be detachably connected to a wall of a building, to facilitate installing and removing of the shutter members separately.

HERBERT S. JONES.
